(57) **CLAIM**

The ornamental design for a spray gun with pattern, as shown and described.

DESCRIPTION

FIG. 1 is a first perspective view of a first embodiment of a spray gun with a wood grain pattern according to the present invention;

FIG. 2 is a second perspective view of the spray gun of FIG. 1;

FIG. 3 is a front view of the spray gun of FIG. 1;

FIG. 4 is a rear view of the spray gun of FIG. 1;

FIG. 5 is a first side view of the spray gun of FIG. 1;

FIG. 6 is a second side view of the spray gun of FIG. 1;

FIG. 7 is a bottom view of the spray gun of FIG. 1;

FIG. 8 is a top view of the spray gun of FIG. 1;

FIG. 9 is a first perspective view of a second embodiment of a spray gun with a wood grain pattern according to the present invention;

FIG. 10 is a second perspective view of the spray gun of FIG. 9;

FIG. 11 is a front view of the spray gun of FIG. 9;

FIG. 12 is a rear view of the spray gun of FIG. 9;

FIG. 13 is a first side view of the spray gun of FIG. 9;

FIG. 14 is a second side view of the spray gun of FIG. 9;

FIG. 15 is a bottom view of the spray gun of FIG. 9; and,

FIG. 16 is a top view of the spray gun of FIG. 9.

The broken lines are for illustrative purposes and form no part of the claimed design.
